US0D1099917S

(12) **United States Design Patent** (10) **Patent No.:** **US D1,099,917 S**
(45) **Date of Patent:** **** Oct. 28, 2025**

(54) **DISPLAY SCREEN OR PORTION THEREOF WITH A GRAPHICAL USER INTERFACE FOR A MEDICAL IMAGING DEVICE**

(71) Applicant: **BHS Technologies GmbH**, Innsbruck (AT)

(72) Inventors: **Luis Fernando Ayuso Perez**, Innsbruck (AT); **Lukas Lederer**, Graz (AT)

(73) Assignee: **BHS Technologies GmbH**, Innsbruck (AT)

(**) Term: **15 Years**

(21) Appl. No.: **29/878,305**

(22) Filed: **Jun. 20, 2023**

Related U.S. Application Data

(62) Division of application No. 29/744,432, filed on Jul. 29, 2020, now Pat. No. Des. 994,679.

CLAIM

The ornamental design for a display screen or portion thereof with a graphical user interface for a medical imaging device, as shown and described.

DESCRIPTION

FIG. 1 is a front view of a display screen or portion thereof with a graphical user interface according to a first exemplary embodiment; and,

FIG. 2 is a front view of a display screen or portion thereof with a graphical user interface according to a second exemplary embodiment.

The broken line showing a display screen or portion thereof is included for the purpose of illustrating portions of the article and forms no part of the claimed design.

1 Claim, 2 Drawing Sheets
